ELECTRIC FLATIRON

Stanley Marvin, Burlingame, Calif., assignor to
B. E. Witkin, Oakland, Calif.

Application September 16, 1938, Serial No. 230,301

8 Claims. (Cl. 219—25)

This invention relates to electric flat irons as used both in the home as well as in tailor shops, laundries, etc., and the principal object of the invention is to provide improvements in the construction of the heating element and the manner of assembling it in the base or sole plate of the iron. One of the important features of the invention is to provide an easily applied and removed heating unit, yet one which will be in close thermal contact over substantially its entire area when in place. Another feature is to do away with securing or clamping bolts passing through the heating unit or margins thereof.

Another feature is a construction which will guard against the access of water to the heating element, when used in an electric steaming iron, and for which the invention was principally developed.

Still another feature is to provide a heating unit which may be removed from the base of the flat iron without disturbing any other parts, such as controlling thermostats, or removal of the handle of the iron, or opening the body shell. Other features and advantages of the construction will appear in the following description and accompanying drawing.

In the drawing:

Figure 1 is an elevation of an electric flat iron incorporating my improvements, and with a portion broken away to show the heating element in its relation to the base of the iron, the sectional portion being taken as from the line 1—1 of Figure 2.

Figure 2 is a horizontal cross section of the iron of Figure 1 as seen from the line 2—2 thereof.

Figure 3 is a greatly enlarged elevation of a portion of the heating element as seen from the line 3—3 of Figure 2.

In further detail, the base or sole plate of the iron is designated 1, the main body portion above the base is designated 2, and above this is a handle 3, all suitably secured together by means not shown, as having no bearing on the present invention; but as the invention has particular value when used in connection with a "steaming iron", that is, one in which a controlled amount of water may be generated into steam and projected through small apertures in the base to moisten the goods being ironed, a water base connection as indicated at 4, a flow controlling valve at 5, and a finger controlled operating valve at 6, though no details of the internal water and steam passages are shown, nor electric heat con-

trol, as they comprise the subject matter of separate co-pending patent applications.

The steam-ejecting passages in the base of the iron are indicated at 7, and the electric cord for supplying the heating current at 13.

The base portion 1 of the flat iron is of the conventional exterior shape in plan as indicated in Figure 2, and is preferably a solid die casting of aluminum alloy or other corrosion resisting metal, and it is formed with a flat wedge-shaped slot 8 near the lower surface of the base. This slot 8 is open at the rear end of the base only, and in plan is of the general shape of the base 1 as indicated except that it is widest at the extreme rear end of the base and constantly becoming smaller toward the front or pointed end, while in vertical section as shown in Figure 1 it decreases in size with a uniform gentle taper toward its front end, and since it has the internal form mentioned it may easily be die-cast from a metal core so that perfectly smooth walls result.

The electric heating element assembly or unit is formed of corresponding wedge shape so that it may be inserted into the slot 8 from its rear open end, and forced tightly in place as by the tap of a hammer, and thus secure a substantially perfect thermal contact with the base or sole plate at both top and bottom of the element over its entire surface. To carry this out I provide a thin flat heating element 9 and mount it firmly on a flat wedge-shaped plate 10 preferably also a die-casting of non-corrodible alloy which projects at its margins 10' slightly beyond the outer edges of the heating element, and I also preferably provide a thin smooth sheet metal cover plate 11 on top of the heating element to prevent possible abrading of the upper side of the heating element when forcing the assembly into the wedge-shaped slot.

The heating element proper preferably consists of flat wire or ribbon resistance coils 9' wound on mica or other heat resisting insulator and likewise preferably embedded in insulating material and covered both sides with mica or other suitable insulating material as at 9''.

The parts of the heating element assemblage may be loosely positioned one upon the other, or secured together as by rivets 12 passing through the members at points to avoid the resistance wire. Plate 10 is formed at its rear end with an upwardly extending wall portion 14 which terminates at the lower face of body portion 2 and also extends rearwardly as a flange 15 which is centrally flattened at 16 and slotted as at 17.

- for the reception of a cap screw 18 which screws into the body portion 2 and/or handle portion 3 to hold the wedge heating element in place as well as secure the handle at this end if desired.
5. Forwardly of wall portion 14 the base member 1 is cut away as at 1' to form an opening for accessibility of the heating element electric terminals 20 from above, and the wall 14 is extended forwardly at both ends as at 1'.
10. One means of securing the base 1 and body 2 together would be cap screws 19 passing from the body 2 into tapped holes positioned along the margins of the base outward from the wedge slot so as to avoid penetrating the same.
15. While I have shown and described a flat wire, mica insulated heating element, this is for illustrative purposes only, and no limitation is to be implied thereby as it is manifest that any desired construction of the heating element itself 20 may be used in carrying out the invention which resides principally in the wedge-shaped assembly, and its cooperating wedge-shaped slot.
- Having thus described my invention, what I claim is:
25. 1. An electric flat iron having a body provided with a base with a flat wedge-shaped slot formed therein open at its thick end to the exterior edge of the base, and an electric heating element of flat wedge form adapted to fit within said slot 30 so as to be removable from the edge of the base.
2. An electric flat iron having a body provided with a base with a flat wedge-shaped slot formed therein open at its thick end to the rear exterior edge of the base, and an electric heating element 35 assembly of flat wedge form adapted to fit within said slot so as to be removable from the edge of the base, said heating element assembly including a flat wedge-shaped metal supporting plate and a heating coil insulatingly mounted thereon.
40. 3. An electric flat iron having a body provided with a base with a flat wedge-shaped slot formed therein open at its thick end to the rear exterior edge of the base, and an electric heating element 45 assembly of flat wedge form adapted to fit within said slot as to be removable from the edge of the base, said heating element assembly including a flat wedge-shaped metal supporting plate and a heating coil insulatingly mounted thereon, and a metal cover plate.
50. 4. An electric flat iron having a body provided

with a base with a flat wedge-shaped slot formed therein open at its thick end to the rear exterior edge of the base, and an electric heating element assembly of flat wedge form adapted to fit within said slot so as to be removable from the 5 edge of the base, said heating element assembly including a flat wedge-shaped metal supporting plate and a heating coil insulatingly mounted thereon, said supporting plate provided with an extension flange projecting beyond the base proper 10 and provided with means for securing it in place.

5. In the construction set out in claim 1, both the slot and the heating element being of tapered form in plan as well as wedge-shaped in thickness, and the open end of the slot being at the 15 large end thereof.

6. An electric flat iron having a solid base provided with a tapered hole extending horizontally from its edge well within the body, and a correspondingly tapered electric heating element fitting within said tapered hole in close thermal contact with the walls thereof and being removable 20 from the edge of the base.

7. An electric flat iron having a solid base provided with a tapered hole extending horizontally 25 from its edge well within the body, and a correspondingly tapered electric heating element fitting within said tapered hole in close thermal contact with the walls thereof and being removable from the edge of the base, said tapered hole being 30 of flat form extending over a relatively large portion of the area of the base when viewed in plan, and being open at the rear edge of the base for insertion and removal of the tapered element.

8. An electric flat iron having a solid base provided with a tapered hole extending horizontally from its edge well within the body, and a correspondingly tapered electric heating element fitting within said tapered hole in close thermal contact with the walls thereof and being removable 40 from the edge of the base, said tapered hole being of flat form extending over a relatively large portion of the area of the base when viewed in plan, and being open at the rear edge of the base for insertion and removal of the tapered element, 45 and said base formed with an opening to the upper side of said element when in place situated adjacent the rear end of the same, for accessibility of its electric terminals from above.

STANLEY MARVIN.
